(57) **CLAIM**

We claim the ornamental design for a shaped tube with a pattern, as shown and described.

DESCRIPTION

FIG. 1 is a perspective view of the shaped tube with a pattern.

FIG. 2 is a front view of the shaped tube of FIG. 1.

FIG. 3 is a left side view of the shaped tube of FIG. 1.

FIG. 4 is a top view of the shaped tube of FIG. 1.

FIG. 5 is a right side view of the shaped tube of FIG. 1.

FIG. 6 is a bottom view of the shaped tube of FIG. 1; and,

FIG. 7 is a back view of the shaped tube of FIG. 1.
